UNITED STATES PATENT OFFICE.

HENRY T. SCHIFF, OF CHICAGO, ILLINOIS, ASSIGNOR TO VITANOLA TALKING MACHINE COMPANY, OF CHICAGO, ILLINOIS, A CORPORATION OF ILLINOIS.

NEEDLE DISPENSER FOR PHONOGRAHES AND LIKE MACHINES.

Application filed April 19, 1920. Serial No. 374,896.

To all whom it may concern:

Be it known that I, HENRY T. SCHIFF, a citizen of the United States, residing at Chicago, in the county of Cook and State 5 of Illinois, have invented certain new and useful Improvements in Needle Dispensers for Phonographs and like Machines, of which the following is a specification.

Heretofore considerable annoyance and inconvenience has been experienced with phonographs and like machines, in that the needles are usually kept in cups or receptacles readily accessible to the operator and from which cups the needles are removed by 10 inserting the fingers thereinto. As the cups or receptacles are of a considerable depth but of a comparatively small diameter and usually contain quite a number of needles arranged promiscuously therein, it is not an 15 uncommon experience for the operator to pierce or prick his fingers while endeavoring to remove a needle from the supply.

It is one of the objects of the present invention to overcome these difficulties, objections and inconveniences and to provide an improved device by means of which the needles may be readily removed from the cup or receptacle when desired, without necessitating the insertion of the fingers of the 20 operator thereinto.

A further object is to provide an improved device of this character which will be simple, durable, cheap, and compact in construction and effective and efficient in operation.

To the attainment of these ends and the accomplishment of other new and useful objects as will appear, the invention consists in the features of novelty in substantially the construction, combination and arrangement 30 of the several parts hereinafter more fully described and claimed and shown in the accompanying drawing illustrating this invention and in which

Figure 1 is a top plan view of a device of this character constructed in accordance with the principles of this invention and showing the same in position with respect to the needle cup or receptacle.

Figure 2 is a view taken on line 2-2, 45 Figure 1.

Figure 3 is a view similar to Figure 2 showing the parts in a different position.

Figure 4 is a sectional view taken on line 4-4 Figure 1.

Figure 5 is a sectional view taken on line 55 5-5 Figure 1.

Referring more particularly to the drawing the numeral 10 designates the top or support of a phonograph cabinet having the usual cups or receptacles 11 for the needles.

Arranged adjacent these cups or receptacles is a support 13 of any desired size and configuration. Pivotally mounted upon the support and extending transversely thereof and preferably to both sides of the support is a bar or rod 14, the extremities 15 of which are preferably bent at substantially right angles thereto to form spaced projecting arms or bars, the extremities 16 of which are preferably rounded as shown and magnetized. The arms 15 may be of any desired length suitable for the purpose and are provided with sleeves 17 of any suitable insulating material and which sleeves terminate short of the extremities 16, for a purpose to 70 be hereinafter set forth.

The support 13 together with the arms 15 are so arranged that when the bar 14 is rocked with respect to the support, the extremities 16 of the arms 15 will be projected 80 into the cups or receptacles 11. This rocking movement may be accomplished in any suitable manner such as by means of an arm or handle 18 which preferably projects in the same direction as the arms 15 and in a 85 convenient position so as to be engaged by the finger of the operator to depress the arms 15 against the stress of an elastic member 19. One end of this elastic member is anchored as at 20 preferably to the support 10 and the other end 21 of the elastic member is preferably secured to an extension 22 of the bar 14. The elastic member 19 tends normally to retract the arms 15 so as to move the extremities 16 out of the cups or receptacles 95 and into the position shown in Figure 2 where the arms will be out of the way to permit the cups or receptacles to be filled.

In use the cups or receptacles generally contain a number of needles arranged promiscuously therein and when it is desired to remove a needle without piercing or pricking the fingers, all that is necessary is to depress the handle 18 to rock the arms 15 against the stress of the elastic member 19 so that 100 the ends 16 of the arms will move from the position shown in Figure 2 to the position shown in Figure 3. The end 16 being mag-

netized a needle will adhere thereto so that when the handle 18 is released, the elastic member 19 will move the parts from the position shown in Figure 3 to the position shown in Figure 2 so that the needle which adheres to the end 16 of the arm may be readily detached therefrom.

The insulating sleeves 17 are provided so as to prevent the needles in the cups or receptacles from adhering to the arm so that the magnetic effect of the arm upon the needles will be confined to the extremities 16 thereof.

While the preferred form of the invention has herein been shown and described, obviously many changes may be made in the details of construction and in the combination and arrangement of the several parts without departing from the spirit of this invention.

What is claimed as new is:—

1. A dispenser for needles for phonographs and like machines embodying a support, an arm pivotally connected with the support and normally projecting over a supply receptacle and adapted to be inserted into the receptacle, the end of the arm being magnetized whereby when it is retracted it will remove a needle from the supply, a

spring connected with the arm and normally operating to move the end of the arm out of the receptacle, and a handle connected with the arm adjacent its pivot, said handle being laterally spaced from the arm and disposed to one side of the receptacle.

2. A dispenser for needles for phonographs and like machines embodying a support, laterally spaced arms pivotally connected with the support intermediate the arms, said arms each normally projecting over a supply receptacle, the end of each arm being magnetized and adapted to be inserted into the respective receptacles, whereby when they are retracted they will remove a needle from the respective supplies, a spring, one end of the spring being connected with the arms and the other end anchored to a fixed support, and tending normally to move the arms out of the receptacles, and a handle secured intermediate the arms and disposed to one side of each of the receptacles, for moving the arms against the stress of the said spring.

In testimony whereof I have signed my name to this specification, on this 12th day of April, A. D. 1920.

HENRY T. SCHIFF.
